United States Patent

Des. 235,369
Patented June 10, 1975

235,369

PORTABLE ELECTRIC WASHER

Downer P. Dykes, Lawrence, Kans., assignor to Rival
Manufacturing Company, Kansas City, Mo.

Filed Dec. 5, 1973, Ser. No. 421,935

Term of patent 14 years

Int. Cl. D15—05

U.S. Cl. D49—1 A

Fig. 1.

Fig. 2.

Fig. 3.

Fig. 4.

Fig. 5.

FIG. 1 is a perspective view of a portable electric washer embodying the invention;

FIG. 2 is a front end elevational view of the washer shown in FIG. 1;

FIG. 3 is a top plan view of the washer shown in FIG. 2;

FIG. 4 is a side elevational view of the washer shown in FIG. 2; and

FIG. 5 is a rear end elevational view of the washer shown in FIG. 2.

I claim:

The ornamental design for a portable electric washer, as shown and described.
